FIG. 7.

Inventor,

Alfred A. Brigh
by Mayo & Harriman
Albany.

UNITED STATES PATENT OFFICE.

ALFRED A. ZIEGLER, OF BOSTON, MASSACHUSETTS.

SIGNAL-LANTERN.

1,209,793.

Specification of Letters Patent. Patented Dec. 26, 1916.

Application filed November 6, 1915. Serial No. 68,108.

To all whom it may concern:

Be it known that I, ALFRED A. ZIEGLER, a citizen of the United States, residing at Boston, in the county of Suffolk and State of Massachusetts, have invented an Improvement in Signal-Lanterns, of which the following is a specification.

My present invention relates to improvements in electric illuminating units, and 10 has particular reference to units of the character designed for use in connection with railway signal-lanterns, being an improvement on my invention disclosed in Letters Patent #1,173,239, dated Feb. 29, 1916, 15 granted to me.

In the type of signal-lanterns herein disclosed it is customary to provide a pair of lamps, and to associate therewith an automatic circuit-controlling mechanism for the 20 lamp-circuits, whereby in case one of the lamps fails, the other will be automatically introduced into the lighting-circuit.

It has heretofore been customary to mount the circuit-controlling mechanism upon a 25 supporting-base or block and to secure it thereto by screws or other fastening-means; and also to connect said mechanism with the lamp-sockets by means of conductor-wires which must be terminally connected or 30 disconnected each time said mechanism is applied to or removed from its supporting-block.

One of the objects of this invention is the provision of means whereby the automatic 35 circuit-controlling means, in assembled condition, may be quickly mounted upon its supporting-block and supported by suitable clamping-means which means is arranged to electrically connect said mechanism with the 40 lamp-sockets, and hence with the lamp.

Figure 1 is a side elevation of an illuminating unit embodying this invention. Fig. 2 is a rear elevation. Fig. 3 is a top plan. Fig. 4 is a side elevation of the automatic 45 circuit-controller. Fig. 5 is a section on line 5-5 of Fig. 4. Fig. 6 is a bottom plan of the circuit-controller, and, Fig. 7 is a dia-grammatic view of the circuits.

My improved illuminating unit, as herein 50 embodied, includes as its broad and essential elements of construction, a lamp-block A, whereon the lamps are mounted, and an automatic circuit-controlling mechanism, generally designated at C, the component 55 parts of which are associated in assembled condition on the conductor-frame B. The

lamp-block A is preferably, rectangular in shape, and is formed of porcelain, or any equivalent non-conducting material. In a raised portion 10 upon the block are formed 60 the two lamp-sockets 11 and 12. In these lamp-sockets are metallic sleeves 13 and 14, having extensions 15 and 16, which lead through openings 17, formed in the portion 10, and constitute conductors upon which 65 spring terminals 19 and 20, formed as clips, are mounted, said members 19 and 20 being secured by rivets or equivalent fastening-members 21.

In the members 13 and 14, are seated insulating gaskets 22, whereon are seated metallic washers 23, through which the conductor-screws 24 and 25 are passed, which screws extend downwardly through the block, and into an L-shaped groove 26. A substantially 70 L-shaped conductor-strip 27 arranged in the groove 26, is electrically connected with the members 19 and 20, as in Fig. 3. A binding-post 28, is mounted upon the block to form a terminal for the conductor-strip 27. 75 Within each socket is arranged a spring contact-sleeve 29.

A groove 30 extending diagonally across the bottom face of the block, receives a conductor-strip 31, the intermediate portion of 80 which is offset as at 32, so that the conductors 27 and 31 may intersect, but will not contact with each other. A binding-post 33 is provided for the conductor-strip 31, and is mounted on the same side of the block as 85 the binding-post 28. A screw, 34, electrically connects the conductor-strip 31 with the spring terminal 35, which is mounted between the members 19 and 20, and is similar thereto.

As shown in detail in Fig. 2, the spring terminals are made as clips 19, 20, 35, each being formed from a strip of copper, or equivalent conducting material, bent U-shape, and its arms are directed inwardly, 100 as at 35^a, and then oppositely curved, producing a pair of opposed arcuate clamping-jaws which will grippingly engage the different cylindrical terminals of the automatic circuit-controlling mechanism, to be 105 described. The gripping-jaws of the members 19 and 20, are provided on their outer edges with the inwardly extending stop lugs 36, by means of which the conductor frame B is held against longitudinal movement upon the base-block, in a manner to 110 be described.

The electro-magnetic circuit controlling means C has the general characteristic features of corresponding means of my aforesaid patent, and also involves structural features of my application #60,105, and includes a magnet 37, an armature 38, a switch-arm 39, and a conductor-plate 40. The magnet is mounted upon one arm of a substantially U-shaped core 41. The armature is terminally pivoted by means of pivot-screws 43, passed through the ears 44, which are preferably formed on the base-member 45 of the conductor-frame B. The downward swinging movement of the armature is limited by the stop-screw 46. To insure a good electrical connection between the switch-arm 39, which member is secured upon the pivoted terminal of the armature, and the conductor-frame, I employ a conductor-wire 47. A spring contact-member attached to the switch-arm 48 is mounted for movement in the opening 48^a, formed in the top frame-member 42, and is engageable with a contact-tongue 49, released from the conductor-plate 40, and extended downwardly therefrom, as in Fig. 5.

The conductor-plate 40 is secured upon a block of insulating material 50, suitably mounted upon the member 42, and is electrically connected to one side of the magnet by a conductor-wire 51. The other side of the magnet is connected by a conductor-wire 52 with a cylindrical terminal 53. The conductor-plate 40, is also connected by a conductor-wire 54, with a cylindrical terminal 55. These terminals 53 and 55, herein shown as sleeves, are mounted on a cylindrical boss 56, of wood or other insulating material. The terminals 53, 55, are insulated from the conductor-frame by a plate or strip of insulating material 57. Screws 58 and 59, having their heads countersunk in the boss 56 secure this member to the conductor-frame. Binding-screws 60 and 61, respectively, receive the terminals of the conducting-wires 52, 54, and secure the sleeves 53 and 55 against movement on the boss. A third terminal 62 is mounted on the boss and is electrically connected with the conductor-frame B by a screw 64.

From the foregoing description it will be apparent that the automatic electro-magnet circuit-controlling means and the contact-members for the terminals of the various conductors thereof are all mounted within or attached to the conductor-frame B, so that the entire mechanism is assembled as a unit and may be applied to or removed from the base-block as a unit. In this connection reference is now had particularly to Fig. 1, wherein it will be seen that the three cylindrical terminals 53, 55 and 62, are of such diameter that they may be forced between the jaws of the three clamp-

ing-members 19, 20 and 35, and the conductor-frame thereby removably secured in position upon the base-block A. The conductor-frame will be held against transverse movement by the members 36, engaging the ends of the boss 56.

Reference will now be had particularly to Fig. 7, from which the operation of the automatic circuit-controlling means will be understood.

The circuit of the lamp in the socket 13 is normally closed, and the circuit through the socket 14 normally open. The first mentioned circuit includes the conductor strip 27, strip 15, spring terminal 19, terminal 53, conductor-wire 52, magnet 37, conductor-wire 51, conductor-plate 40, conductor-wire 54, terminal 55, spring terminal 35, and conductor-strip 31. When this circuit is closed the magnet is energized and the armature holds the switch-arm in open circuit position, whereby the circuit through the lamp of socket 14 is broken. The interruption of the circuit of socket 13 deenergizes the magnet however, and allows the armatures to drop, thereby engaging the switch-arm with the tongue 49 of conductor-plate 40. The circuit thus established through the lamp of socket 14 includes, conductor-strip 27, strip 16, spring-terminal 20, cylindrical-terminal 62, conductor-frame B, switch-arm 39, conductor-plate 40, conductor-wire 54, cylindrical-terminal 55, spring-terminal 35, and conductor-strip 31.

I claim:

1. In an electrical illuminating-unit, a lamp-block, lamp-sockets thereon, conductors leading from the lamp-sockets, electro-magnetic mechanism controlling the circuits through the lamp-sockets, and means for removably securing the said mechanism upon the lamp-block, said means forming the conductors for electrically connecting the said mechanism and conductors of the lamp-sockets.

2. A lamp-block, having a pair of lamp-sockets, automatic electro-magnetic means controlling the circuits of the two lamp-sockets, a supporting-frame for the said means, a plurality of terminals carried by the frame and a plurality of spring-terminals mounted upon the block to receive the first-mentioned terminals, and thereby removably support the said means upon the block, said spring-terminals being connected in the circuits of the two lamps for electrically connecting the said means in the circuits of the two lamp-sockets.

3. In an electrical illuminating-unit, a lamp-block having a pair of lamp-sockets, a plurality of conductors included in the circuits of the two sockets, a plurality of spring-clips forming terminals for said conductors, an automatic electro-magnetic means for controlling the circuits in the

two sockets, a frame supporting the means, and a plurality of cylindrical terminals for the circuits through said means, said cylindrical terminals being receivable in the 5 spring-terminals whereby the said means is removably secured upon the block, and the circuits of the means connected in the circuits of the sockets.

4. In an electric illuminating-unit, a base-block, lamp-sockets therein, a pair of binding-posts, a conductor connecting the first of said binding-posts with both of said sockets, conductors leading from each of said 10 sockets and insulated from said first-mentioned conductor, an automatic electro-magnetic mechanism operable for controlling the circuits through the lamp-sockets and a plurality of separated spring-terminals mounted upon the base-block and engageable with 15 the said mechanism for removably securing the same upon the base-block, certain of said spring-terminals being positioned to electrically connect the mechanism with the conductors leading from the lamp-sockets, and 20 another spring-terminal serving to electrically connect the mechanism with the second binding-post.

5. An electrical illuminating-unit including a lamp-block having a pair of lamp- 30 sockets, an automatic electro-magnetic circuit controlling means for the circuits of the sockets, a frame supporting said means and with respect to which said means is fixed, a plurality of cylindrical terminals attached 35 to the frame and the circuits thereof, a plurality of spring-clips secured upon the lamp-block and forming terminals for the circuits of the two sockets, said spring-clips being adapted to receive the cylindrical terminals 40 for detachably securing the said means upon the block and for connecting the circuits through said means with the circuits of the two sockets, each of said spring-clips comprising a pair of opposed resilient 45 clamping-jaws adapted to embrace a cylindrical terminal.

6. An electrical illuminating-unit including a lamp-block having a pair of lamp-sockets, an automatic electro-magnetic circuit 50 controlling means for the circuits of the sockets, a frame supporting said means and with respect to which said means is fixed, a plurality of cylindrical terminals at-

tached to the frame and the circuits thereof, a plurality of spring-clips secured upon the 55 lamp-block and forming terminals for the circuits of the two sockets, said spring-clips being adapted to receive the cylindrical terminals for detachably securing the said means upon the block and for connecting 60 the circuits through said means with the circuits of the two sockets, each of said spring-clips comprising a pair of opposed resilient clamping-jaws adapted to embrace a cylindrical terminal, and stop-members formed 65 upon certain of said spring-clips for holding the frame against movement in the plane of its base-portion.

7. An electrical illuminating-unit including a lamp-block, a pair of lamp-sockets 70 therein, an automatic electro-magnetic means for governing the circuits through the two lamp-sockets, a frame supporting said means, a cylindrical boss secured to the frame, a plurality of terminal sleeves mounted on the boss and a plurality of spring-terminals adapted to detachably receive the 75 said sleeves, said spring-terminals being secured upon the lamp-block and being connected in the circuits of the lamp-sockets. 80

8. An electrical illuminating-unit including a lamp-block, a pair of lamp-sockets therein, an automatic electro-magnetic means for governing the circuits through the two lamp-sockets, a frame supporting said 85 means, a cylindrical boss secured to the frame, a plurality of terminal sleeves mounted on the boss and a plurality of spring-terminals adapted to detachably receive the 90 said sleeves, said spring-terminals being secured upon the lamp-block and being connected in the circuits of the lamp-sockets, each of said spring-clips being formed from a strip of metal bent into a U, having oppositely curved clamping-jaws, the terminally 95 located spring-terminals having stop members which are engageable with the boss for holding the frame against transverse movement upon the block.

In testimony whereof, I have signed my 100 name to this specification, in the presence of two subscribing witnesses.

ALFRED A. ZIEGLER.
